UNITED STATES PATENT OFFICE

2,005,289

VETERINARY INSTRUMENT

Edgar Ellsworth, McLoud, Okla.

Application November 23, 1934, Serial No. 754,547

1 Claim. (Cl. 128—245)

The present invention relates to new and useful improvements in veterinary instruments and has for its primary object to provide, in a manner as hereinafter set forth, a device comprising a novel construction, combination and arrangement of parts through the medium of which enemas, for example, may be expeditiously given to cattle, horses and other stock.

Another important object of the invention is to provide an instrument of the aforementioned character comprising novel means for clamping the rectum in a manner to prevent leakage but without causing discomfort to the animal.

Other objects of the invention are to provide an instrument of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a plan view of a veterinary instrument constructed in accordance with the present invention.

Figure 2 is a view in longitudinal section through the instrument.

Figure 3 is a detail view in elevation of the valve.

Figure 4 is a detail view in side elevation of the member in which the valve is operable.

Figure 5 is a cross sectional view, taken substantially on the line 5—5 of Figure 1.

Referring now to the drawings in detail, it will be seen that the embodiment of the invention which has been illustrated comprises a substantially U-shaped frame 1 of suitable metal having formed integrally with its forward or open end a ring 2. The forward portion of the ring 2 has formed therein an internal groove 3 in which is mounted a tubular annulus of suitable resilient or compressible material, preferably rubber, which constitutes a valve seat 4.

The bight portion of the frame 1 has formed thereon a rearwardly extending boss 5 and said bight portion is provided with a longitudinal groove or channel 6 for the reception of a tubular stem 7, the rear portion of which is externally threaded, as at 8. Mounted in the rear end of the stem 7 is a nipple 9 for connection with a flexible conduit from a source of fluid supply. Return flow of the fluid through the nipple 9 is prevented by a ball check valve 10 (see Figure 2) which is mounted in said nipple.

Formed integrally with the forward end of the

stem 7 is a substantially conical head 11 through which the passage 12 in said stem 7 also extends. Engaged with the rear end of the head 11 is a ring 13 of suitable compressible material, preferably rubber, which is secured in position by a retaining nut 14 which is threaded on the enlarged forward end portion 15 of the stem 7. A nut 16 is threadedly mounted on the portion 8 of the stem 7 and engageable with the boss 5 for drawing the head 7 toward the resilient seat 10 for clamping the rectum therebetween.

In use, the instrument is inserted and the nut 16, which is provided with operating handles 17, is actuated to clamp the outer end or mouth of the rectum between the elements 13 and 4, thus sealing this point against leakage of the fluid without causing discomfort to the animal. With a rubber hose or other suitable conduit connected to the nipple 9 the fluid from the source of supply may then be introduced into the animal through the passage 12, as will be apparent. The check valve 10 prevents return flow of the fluid through the stem 7. In Figure 1 of the drawings, a portion of a conduit is indicated by the reference numeral 18.

It is believed that the many advantages of a veterinary instrument constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

What is claimed is:—

A veterinary instrument comprising a substantially U-shaped frame having a ring integral with the open end thereof, the bight portion of the frame having a longitudinally extending groove therein, said ring having a channel in its inner periphery, a compressible annulus mounted in said channel and having a portion thereof projecting beyond the inner side of said ring and defining a seat, a stem extending through said groove and extending through said ring, a frustoconical shaped head on said stem, a compressible bevelled edge washer on said stem abutting the rear portion of said head, a nut on said stem for securing the washer in position, said washer being cooperable with the compressible annulus for clamping a portion of the rectum therebetween, said stem and said head being provided with a fluid passage therein and a clamping nut threadedly mounted on said stem and engageable with the bight portion of the frame for moving the stem within the frame.

EDGAR ELLSWORTH.
